UNITED STATES PATENT OFFICE.

BOONE V. H. JOHNSON, OF ST. LOUIS, MISSOURI, ASSIGNOR TO DOUBLE BODY BOLSTER CO., A CORPORATION OF NEW JERSEY.

RAILROAD-CAR.

1,069,957.

Specification of Letters Patent.

BEST AVAILABLE COPY

Patented Aug. 12, 1913.

Application filed January 28, 1911. Serial No. 604,163.

To all whom it may concern:

Be it known that I, BOONE V. H. JOHNSON, a citizen of the United States, residing at St. Louis, in the State of Missouri, have invented a new and useful Improvement 5 in Railroad-Cars, of which the following is a specification.

My invention relates particularly to the sides of a car body, and is especially applicable to a car body having structural metallic, or composite metallic and wood, sides, combined with cast steel or structural metallic ends and underframe, and my invention has for its object principally, to provide 15 a car body having its ends and the adjoining end portions of its sides interlocked and connected together so as to produce a strong and rigid construction for resisting end shock and telescoping of the car.

20 It consists in features of novelty as hereinafter described and claimed, reference being had to the accompanying drawing forming part of this specification, whereon—

Figure 1, is a side elevation of an end portion of one of the sides of a car body, constructed according to my invention; Fig. 2, a horizontal section therethrough and through the adjoining end portion of the body (broken away), on line 2, 2, in Fig. 1, 25 showing the corresponding part of the underframe in top plan view; Fig. 3, a vertical transverse section to enlarged scale through one-half of the car body, on line 3, 3, in Fig. 1; Figs. 4 and 5, horizontal sections 30 to enlarged scale through the end and succeeding inner upright members of the side on lines 4, 4, and 5, 5, respectively, in Fig. 1; Fig. 6, a similar view to Fig. 3, showing a modification of the roof, and Figs. 7, and 35 8, diagrammatic views to reduced scale, corresponding to Fig. 1, showing the entire side of a passenger and caboose car body respectively, constructed according to my invention.

40 Like letters and numerals of reference denote like parts in all the figures.

Referring to Figs. 1 to 5, *a* represents an end portion of the side of a car body, *b* the end (broken away) of the car body adjoining the side portion *a*, and *c* the corresponding part of the car underframe.

According to my invention, the end portion *a* of the side of the car body (hereinafter termed "the casting") is composed 45 preferably, of cast steel in a single piece,

extending longitudinally for a suitable distance along the car from the end *b*, and vertically, preferably, to the plate or full height of the side. The component members of the casting *a* may be of any desired configuration and cross section respectively, as best calculated to impart strength and rigidity to the casting, such as shown on the drawing, in which the casting *a* consists of an outer and inner T-shaped end member 1, 1', respectively, a series of upright cross-shaped members 2 intermediate to the end members 1, 1', a bottom and top horizontal T-shaped member 3, 3', respectively, suitable horizontal intermediate members 4 connecting the upright members 1, 1', 2, and a diagonally disposed member 5 extending from the top corner of the outer end of the casting *a*, to the bottom of the casting *a* at the junction of the bottom member 3' with the upright member 2 immediately adjacent to the end member 1. All the parts just described are connected together and arranged to conform to the window openings 6 and to form intermediate lightening openings 7.

The casting *a* is supported on and fixed to the underframe *c*, which consists in the present case, of the body-bolster 8 (broken away), one at each end of the car, and its extension 8' to the end *b* of the car body, the 50 bolster 8 and its extension 8', being preferably, composed of cast steel in one piece throughout and formed at each side with a bottom outwardly projecting flange 9 to which is riveted the bottom outwardly projecting overlying flange 10 of the longitudinal Z-bar 11 which connects the bolster 8 and extension 8', to the corresponding bolster and extension at the other end of the car, the other members of the underframe *c* 55 being of any suitable construction and arrangement according to the particular type of metallic underframe used.

The casting *a* is fixed in the present case at the bottom, preferably by rivets 12 to the 60 combined flanges 9 and 10 of the bolster 8 with its extension 8', and of the Z-bar 11 respectively. Or the casting *a* may be otherwise fixed at the bottom to the underframe *c* as found most desirable in practice.

The side of the car body between the inner ends of the castings *a* may be of any suitable well-known structural rolled metal, such as indicated by dotted lines in Fig. 1, 65 or of any other ordinary construction and 70

as so built up, forms no part of my invention, but if desired the entire side of the car body may consist of a series of sections or castings *a* fixed together at their meeting ends, in lieu of the ordinary built up construction, as seen in Fig. 7, which shows my invention applied to a passenger car, and in the case of a caboose or analogous car the entire side may be of cast steel in a single 10 piece as shown in Fig. 8.

The metallic end *b* of the car body, which may be of built up structural rolled members, but preferably, of cast steel in a single piece as shown on the drawing, is preferably, 15 formed according to my invention along each side edge or thereabout and adjacent thereto on its inner face with two parallel upright beads or projections *13* which overlap the outer and inner edges of end member *1* of the side casting *a* so as to interlock the latter with the end *b* and thereby prevent the sides of the car from spreading, and the telescoping of the car in case of collision, the end *b* being furthermore riveted 20 to the end members *1* of the casting *a* and at the bottom to the underframe *c* in any desirable manner.

In combination with the side casting *a*

I may use a roof section *14* (Figs. 1 and 3) of the desired shape, and composed preferably, of cast steel integral throughout and extending preferably, the entire length of the casting *a*, the roof section *14* being preferably, flanged and fixed at its lower longitudinal edge by rivets *15* to the top member *3* of the casting *a*, and at its upper longitudinal edge by a flange *16* and rivets *17* to the metallic sill *18*. Or the entire roof framing including the two opposite sections *14* and the intermediate ventilator framing *40* *19* (with the hoods, not shown) may be integral as shown in Fig. 6.

I make no claim to the use of a metallic end "per se" for a railroad car, but 45 What I do claim and desire to secure by Letters Patent is: —

A car side composed of one or more cast metal sections connected together, said sections having integral ribs traversing their area and serving to transmit the load by forming the principal load-carrying elements of the car.

BOONE V. H. JOHNSON.
